UNITED STATES PATENT OFFICE.

WALTER BRINTON, OF HIBRIDGE, NEW JERSEY, ASSIGNOR TO TAYLOR IRON AND STEEL COMPANY, A CORPORATION OF NEW JERSEY.

SAFE OR VAULT.

SPECIFICATION forming part of Letters Patent No. 793,121, dated June 27, 1905.

Application filed June 17, 1904. Serial No. 212,924.

To all whom it may concern:

Be it known that I, WALTER BRINTON, a citizen of the United States, residing in Highbridge, in the county of Hunterdon and State 5 of New Jersey, have invented certain new and useful Improvements in Safes or Vaults, of which the following is a specification.

This invention relates to safes or vaults, more particularly to that class thereof known 10 as "burglar-proof" safes and vaults, the object of the invention being to provide an improved burglar-proof structure with its door-joint protected in a somewhat similar manner to that shown and described in my contemporane- 15 ously-pending application, Serial No. 194,655, filed February 23, 1904, now Patent No. 771,704, dated October 4, 1904, and which fully discloses the advantages of a reinforcing or protecting means such as that about to be 20 described and to which reference is made, so that a more complete statement than that herein set forth is not deemed necessary.

In the drawings accompanying and forming part of this specification, Figure 1 is a side 25 partly vertical sectional view of this improved safe or vault body. Fig. 2 is a vertical sectional view of the door. Fig. 3 is a view similar to Fig. 1, but with the door seated in its jamb. Fig. 4 is also a vertical sectional view 30 of a somewhat different form of door from that shown in Figs. 2 and 3, and Fig. 5 is a sectional view of a portion of a door similar to that shown in Fig. 4 and a body constructed differently from the body shown in Fig. 3.

Similar characters of reference designate 35 corresponding parts throughout the several figures.

In the improvement shown and described 40 in my said application hereinbefore referred 40 to the safe or vault body only is provided with reinforcing or protecting inserts, such inserts being shown preferably flush with the outer surface of the body. In the present improvement these inserts in the body project beyond 45 the outer surface of such body and are located not in the bead formed around the doorway, but in the front of the body proper, which, however, in the form shown in Figs. 1 and 3 and which is the desirable and practicable form

projects beyond a relatively flat surface located 50 at the outer terminus of the jamb-surface, which is substantially flush with a similar or matching surface contiguous thereto located on the door, so that such surfaces are protected by the projecting portion of the front from sledging 55 or analogous operations with a view of opening the joint around the door. In the present improvement also the door is shown provided with inserts which may be located therein in a similar manner to that shown and 60 described in the said application—that is to say, substantially flush with the outer surface of such door, Figs. 4, 5—or they may project beyond the outer surface thereof, as illustrated in Figs. 2 and 3. 65

In those safes or vaults which do not have the joint around the door provided with a grinding—that is, a ground—surface and protected in the manner shown and described herein these improved inserts, however, could 70 all be used either in the door or body, or in both, as shown in Fig. 5, but not with the same advantage and security as when located in a bead or projecting portion of the body front, so that their bottoms or inner faces are 75 substantially in line with the ground-surfaces of the door and body.

The safe or vault body preferably comprises an integral body 2, formed, when a superior structure is desired, of unmachineable metal—80 such, for instance, as manganese steel—which when heat-treated has superior resisting qualities, provided with a circular doorway 3, the front 4 of which body projects beyond an annular surface 5, located at and around the 85 outer terminus of the jamb-surface 6. This annular surface may in practice, if preferred, be square or substantially square with the jamb-surface. The body is also preferably provided with an interiorly-located circular 90 flange 7, preferably of considerable depth, prolonging the jamb-surface and forming between it and the walls of the body a recess or space whereby substantial uniformity of the material around the jamb may be preserved 95 during the casting of the body and also during the heat treatment thereof if the body is subjected to this step, and which flange is

shown connected to the wall of the body by a series of ribs or braces 8, preferably integral with the flange and body-wall. The door 9, shown as a circular integral structure preferably formed of the same material of which the body is made, preferably comprises a body 10 and an inwardly-extending flange 11. The door is provided contiguous to its joint-surface at the outer terminus thereof with an 5 annular surface 12, which is flush or substantially flush with the annular surface of the body. This annular surface 12 may in practice, if preferred, be square or substantially square with the joint-surface of the door. 10 Such meeting or matching surfaces—that is, surfaces which when properly ground result in a flush or substantially flush metal-to-metal tight joint—form grinding-surfaces, so that when the door is firmly seated in its jamb and 15 the two surfaces 5 and 12 ground to be flush, or substantially so, with each other there is no space at or around the joint for the insertion of a wedge or explosive fluid to assist in the forcing out of the door.

20 The door in the present instance is shown as a rotary door, although the present features could be used in connection with a door secured to its seat by bolts, if desired, and for that purpose suitable lugs or locking-surfaces 13 are provided, which are more fully described 25 in my said application hereinbefore referred to.

30 In the form of door shown in Figs. 2 and 3 it will be observed that the front of the door 9' projects beyond the annular ground surface 12, thus to a certain extent protecting it. The front of the safe or vault body is reinforced by a series of members 14, interlocked with such front during the casting of the body, 35 they being shown as wedge-shaped, whereby they dovetail into corresponding pockets or recesses in the body front, and so held against displacement. These members are formed of 40 a metal composition different from that of which the body is formed—such, for instance, as chrome or analogous hard steel—being located in position to receive the blows of a sledge or other tool, so as to resist such blows and prevent peening of the metal of the body adjacent to the joint. In the present construction 45 of safe these hard-metal inserts are located at intervals around the doorway and in the preferred form of safe with their inner surfaces 50 substantially in line with the annular relatively flat ground-surface 5, located at the outer terminus of the jamb, so that even should one or more of the inserts be forced out of their pockets the inner wall 16 of such pockets or recesses would not be below or beyond the joint-surface. It is partly for this reason that the 55 construction shown in Figs. 1 and 3 is an advantage over that shown in Fig. 5. These inserts in the form shown in Figs. 1 and 3 project beyond the surface of the body and preferably have their edges curved or rounded. By

projecting the inserts beyond the surface of the body they intercept a sledge or other tool, so that it is not practicable to even strike heavy blows upon the metal of such body adjacent thereto. The inserts both on the door and body, 70 may be formed similar to that shown, or they may be formed with sharpened or projecting portions, as found desirable. Similar inserts 75 to those just described may be located in the door either with their outer surfaces flush therewith, as in Figs. 4 and 5, or projecting beyond, as in Figs. 2 and 3, the amount of projection being determined according to circumstances. The inserts in the door may alternate, if desired, 80 with the inserts in the body. When the inserts are flush with the door or body, as shown in Figs. 4 and 5, they may be inserted so as to project slightly and then ground to conform to the surface of the part in which they are located.

85 By providing two sets of inserts, one located in the door and one in the body adjacent to such door, and both of which project beyond the door and body, the use of a sledge or analogous tool on the material of the body and door is intercepted. Such a structure, with its series of bristling projections around the door-joint, thus has what might properly be considered a porcupine formation, materially 90 reinforcing the safe or vault. It, moreover, 95 assists in the production of a better casting, since the inserts act as chills, as pointed out in my said application hereinbefore referred to. These protecting or reinforcing inserts could be located along joints other than that 100 shown, if desired, should the vault body or door be made of several members instead of as an integral structure, as shown herein.

One of the features which I consider a very valuable one is the formation of such body 105 so that within the forward outer boundary of the front there is located an annular relatively flat surface 5, forming the outer terminus of the jamb-surface and matching and flush or substantially flush with a similar contiguous 110 surface 12 formed on the door. In the said 115 application hereinbefore referred to and in the contemporaneously-pending application filed by myself and Walter Gaston September 30, 1903, Serial No. 175,161, this feature was provided; but the forwardly-projecting portion 120 at the base of which this annular surface was located was in the nature of a bead. In the present improvement, however, it will be seen that a distinct bead, separate and independent 125 of the front, is done away with, notwithstanding which, however, the front of the safe, or a part thereof, still projects beyond the joint around the door, and this without the formation of a V-shaped space or recess, as has heretofore been the case whenever the front of the safe and the door projected beyond the jamb, so that the use of a wedge is not in any way assisted. In other words, the door and body 130 matching surfaces 5 and 12 abruptly termi-

nate the joint-surface at the door, sharply diverging away therefrom at each side thereof, while the body front, or a part thereof, projects beyond such matching surfaces, and thus 5 protects the same and materially interferes with the use of a sledge or analogous tool, forming what may be termed a "depressed joint," since it is within the outer surface of the front portion of the safe-body adjacent to 10 the door.

In the present structure the wall 20, which merges into the flat surface 5 and into the outer forward surface 21, is curved, and this 15 wall is preferably of an ogee or substantially ogee formation.

Suitable means may be used when the door is a rotary door for locking the safe against rotation after it is seated in its jamb; but as this does not constitute a part of my present 20 invention further reference thereto is deemed unnecessary.

Having thus described my invention, I claim—

1. A safe or vault body having at the outer 25 terminus of its jamb-surface and contiguous to and around the same a relatively flat surface beyond which the front of such body projects.

2. A safe or vault body having at the outer terminus of its jamb-surface and contiguous 30 to and around the same a relatively flat surface beyond which the front of such body projects, the wall merging into such surface and the forward surface of the projecting front having an ogee or substantially ogee formation.

3. A safe or vault body formed of unmachineable metal having a circular doorway and provided at the outer terminus of its jamb-surface and contiguous and around the same 40 with an annular surface located at an angle to the jamb, beyond which the front of the body projects.

4. A safe or vault body formed of unmachineable metal having a circular doorway and 45 provided at the outer terminus of its jamb-surface and contiguous and around the same with an annular ground surface square or substantially square with such jamb-surface and beyond which the front of the body projects.

5. A safe or vault body having at the outer terminus of its jamb-surface and contiguous 50 to and around the same a relatively flat surface beyond which the front of such body projects, and a door fitting into said jamb and having its front surface contiguous to such flat surface flush or substantially flush therewith.

6. A safe or vault body formed of unmachineable metal having a circular doorway and 60 provided at the outer terminus of its jamb-surface and contiguous and around the same with an annular ground surface located at an angle to the jamb and beyond which the front of the body projects, and a circular door also 65 formed of unmachineable metal fitting into

said jamb and having contiguous to its edge a similar annular surface flush or substantially flush therewith.

7. A safe or vault door having at the outer terminus of its joint-surface and contiguous to 70 and around the same a relatively flat surface beyond which the front of such door projects.

8. A circular safe or vault door formed of unmachineable metal having at the outer terminus of its joint-surface and contiguous to 75 and around the same an annular surface located at an angle to the door edge and beyond which the front of such door projects.

9. A circular safe or vault door formed of unmachineable metal having at the outer terminus of its joint-surface and contiguous to 80 and around the same an annular ground surface square or substantially square with such joint-surface and beyond which the front of such door projects.

10. A safe or vault body having a circular doorway, and a circular door fitting therein, said door having contiguous to its joint-surface at and around the outer terminus thereof a relatively flat annular surface and said 90 body having its front projecting beyond such flat annular surface.

11. A safe or vault structure comprising a body having a circular doorway and a door fitting therein, said structure having around and 95 contiguous to the door-joint at the outer terminus thereof a relatively flat annular surface beyond which the front of the body projects.

12. An integral safe or vault body formed 100 of unmachineable metal having a circular doorway, and an integral circular door likewise formed of unmachineable metal fitting said doorway, said body having at and around the outer terminus of its jamb-surface an annular ground surface located at an angle to the jamb and beyond which a front portion of such body materially projects.

13. A safe or vault structure comprising a body and a circular door, said body having its 110 wall adjacent to the door projecting beyond the outer terminus of the joint-surface, and said structure having an annular surface abruptly terminating the joint-surface of the door and located within the outer terminus 115 of such projecting wall.

14. A safe or vault comprising an integral body and an integral circular door each formed of unmachineable metal, the front wall of said body projecting beyond the joint-surface of 120 the door, and said body and door having a pair of annular matching surfaces located within the forward boundary of such front wall, and abruptly terminating the joint-surface at the door.

15. A safe or vault comprising an integral body and an integral circular door each formed of unmachineable metal, the front wall of said body projecting beyond the joint-surface of 125 the door, and said body and door having a 130

- pair of annular matching surfaces located within the forward boundary of such front wall, and abruptly terminating the joint-surface at the door, such surfaces being located 5 substantially parallel to the plane of the door.
16. A safe or vault comprising a body and a circular door, said body having its wall adjacent to the door projecting beyond the joint-surface of the door, and said door or body 10 having a pair of annular matching surfaces abruptly terminating the joint-surface at the front of the safe or vault and within the outer terminus of such projecting wall.
17. A safe or vault body having means located in and formed separate from the front thereof adjacent to the door-joint, and projecting forwardly of the surface of such body 15 for reinforcing the same.
18. An integral safe or vault body formed 20 of unmachineable metal and having a circular doorway, and reinforcing means located in the front thereof around the door-joint and formed of a composition of metal different from the metal of which such body is formed
- 25 and projecting forwardly of the surface of such body to intercept a sledge or analogous tool, thereby to prevent the peening of the metal adjacent to such joint.
19. A safe or vault body having a series of 30 inserts located at intervals in the front thereof adjacent to and around the door-joint and projecting forwardly of the surface of such body.
20. A safe or vault body having located side 35 by side in the front thereof around the door-joint, a series of wedge-shaped inserts projecting forwardly of the surface of the body.
21. A safe or vault door having reinforcing means located in and formed separate from 40 the front thereof and adjacent to its edge and projecting forwardly of such door.
22. A safe or vault door having a series of reinforcing devices located at intervals in the front thereof adjacent to its edge.
23. A safe or vault door having a series of 45 projecting reinforcing devices located in the door adjacent to its edge.
24. A circular safe or vault door having a circular series of wedge-shaped inserts located 50 in the front of such door around and adjacent to its edge.
25. A safe or vault door having a series of reinforcing hard - metal inserts interlocked with the metal of such door at the front thereof.
26. An integral safe or vault door formed 55 of unmachineable metal having located therein at the front thereof reinforcing means formed of a composition of metal different from the metal composition of which the door 60 is formed.
27. A safe or vault comprising a body and a door, each having located in the front thereof around and adjacent to the joint reinforcing means of a composition of metal different 65 from that of which such body and door are formed.
28. A safe or vault comprising an integral body and an integral door, each having located in the front thereof around and adjacent to the door-joint, reinforcing means formed 70 of a composition of metal different from that of which such body and door are formed, and projecting respectively beyond the surfaces of the body and door.
29. A safe or vault comprising a body and 75 a door, each having located in the front thereof around and adjacent to the door-joint, reinforcing means comprising a series of wedge-shaped inserts located side by side and projecting beyond the surfaces of the door and body respectively.
30. A safe or vault comprising an integral body and an integral circular door, each formed of unmachineable metal and having interlocked in the front thereof entirely around 80 and adjacent to the door-joint a series of protecting-inserts located at intervals.
31. A safe or vault door having chrome or analogous hard - steel reinforcing means located therein.
32. A heat-treated manganese-steel safe or 90 vault door having chrome or analogous hard-steel inserts located therein.
33. An unmachineable cast - steel safe or vault door having chrome or analogous hard- 95 steel inserts located therein during the casting thereof.
34. An unmachineable cast - steel safe or vault door having chrome or analogous hard-steel inserts located therein and projecting 100 forwardly of the surface thereof.
35. A safe or vault body having chrome or analogous hard-steel reinforcing means located therein and projecting forwardly of the surface thereof.
36. An unmachineable-metal safe or vault body having chrome or analogous hard-steel inserts located therein at intervals around its jamb and projecting forwardly of the surface 105 of such body.
37. A heat-treated manganese-steel safe or vault body having chrome or analogous hard-steel inserts located therein at intervals, around its jamb and projecting forwardly of the surface of such body.
38. A safe or vault made up of a plurality of members with its joint protected by means located in one or both of such members and projecting forwardly thereof.
39. A safe or vault made up of several 110 members with its joint protected by a plurality of interlocked inserts located in one or both of such members and formed of chrome or analogous hard steel projecting forwardly 115 of the surface of the metal at such joint.
40. A safe or vault body having a portion 120 of its front projecting beyond its door-joint, and protecting-inserts located at intervals in

nate the joint-surface at the door, sharply diverging away therefrom at each side thereof, while the body front, or a part thereof, projects beyond such matching surfaces, and thus 5 protects the same and materially interferes with the use of a sledge or analogous tool, forming what may be termed a "depressed joint," since it is within the outer surface of the front portion of the safe-body adjacent to 10 the door.

In the present structure the wall 20, which merges into the flat surface 5 and into the outer forward surface 21, is curved, and this 15 wall is preferably of an ogee or substantially ogee formation.

Suitable means may be used when the door is a rotary door for locking the safe against rotation after it is seated in its jamb; but as 20 this does not constitute a part of my present invention further reference thereto is deemed unnecessary.

Having thus described my invention, I claim—

1. A safe or vault body having at the outer 25 terminus of its jamb-surface and contiguous to and around the same a relatively flat surface beyond which the front of such body projects.

2. A safe or vault body having at the outer terminus of its jamb-surface and contiguous 30 to and around the same a relatively flat surface beyond which the front of such body projects, the wall merging into such surface and the forward surface of the projecting front having an ogee or substantially ogee formation.

3. A safe or vault body formed of unmachineable metal having a circular doorway and provided at the outer terminus of its jamb-surface and contiguous and around the same 40 with an annular surface located at an angle to the jamb, beyond which the front of the body projects.

4. A safe or vault body formed of unmachineable metal having a circular doorway and 45 provided at the outer terminus of its jamb-surface and contiguous and around the same with an annular ground surface square or substantially square with such jamb-surface and beyond which the front of the body projects.

5. A safe or vault body having at the outer terminus of its jamb-surface and contiguous 50 to and around the same a relatively flat surface beyond which the front of such body projects, and a door fitting into said jamb and having its front surface contiguous to such flat surface flush or substantially flush therewith.

6. A safe or vault body formed of unmachineable metal having a circular doorway and 60 provided at the outer terminus of its jamb-surface and contiguous and around the same with an annular ground surface located at an angle to the jamb and beyond which the front of the body projects, and a circular door also 65 formed of unmachineable metal fitting into

said jamb and having contiguous to its edge a similar annular surface flush or substantially flush therewith.

7. A safe or vault door having at the outer terminus of its joint-surface and contiguous to 70 and around the same a relatively flat surface beyond which the front of such door projects.

8. A circular safe or vault door formed of unmachineable metal having at the outer terminus of its joint-surface and contiguous to 75 and around the same an annular surface located at an angle to the door edge and beyond which the front of such door projects.

9. A circular safe or vault door formed of unmachineable metal having at the outer terminus of its joint-surface and contiguous to 80 and around the same an annular ground surface square or substantially square with such joint-surface and beyond which the front of such door projects.

10. A safe or vault body having a circular doorway, and a circular door fitting therein, said door having contiguous to its joint-surface at and around the outer terminus thereof of a relatively flat annular surface and said 90 body having its front projecting beyond such flat annular surface.

11. A safe or vault structure comprising a body having a circular doorway and a door fitting therein, said structure having around and 95 contiguous to the door-joint at the outer terminus thereof a relatively flat annular surface beyond which the front of the body projects.

12. An integral safe or vault body formed 100 of unmachineable metal having a circular doorway, and an integral circular door likewise formed of unmachineable metal fitting said doorway, said body having at and around the outer terminus of its jamb-surface an annular ground surface located at an angle to the 105 jamb and beyond which a front portion of such body materially projects.

13. A safe or vault structure comprising a body and a circular door, said body having its 110 wall adjacent to the door projecting beyond the outer terminus of the joint-surface, and said structure having an annular surface abruptly terminating the joint-surface of the door and located within the outer terminus 115 of such projecting wall.

14. A safe or vault comprising an integral body and an integral circular door each formed of unmachineable metal, the front wall of said body projecting beyond the joint-surface of 120 the door, and said body and door having a pair of annular matching surfaces located within the forward boundary of such front wall, and abruptly terminating the joint-surface at the door.

15. A safe or vault comprising an integral body and an integral circular door each formed of unmachineable metal, the front wall of said body projecting beyond the joint-surface of 125 the door, and said body and door having a 130

1. pair of annular matching surfaces located within the forward boundary of such front wall, and abruptly terminating the joint-surface at the door, such surfaces being located substantially parallel to the plane of the door. 5
16. A safe or vault comprising a body and a circular door, said body having its wall adjacent to the door projecting beyond the joint-surface of the door, and said door or body 10 having a pair of annular matching surfaces abruptly terminating the joint-surface at the front of the safe or vault and within the outer terminus of such projecting wall. 15
17. A safe or vault body having means located in and formed separate from the front thereof adjacent to the door-joint, and projecting forwardly of the surface of such body for reinforcing the same. 20
18. An integral safe or vault body formed of unmachineable metal and having a circular doorway, and reinforcing means located in the front thereof around the door-joint and formed of a composition of metal different from the metal of which such body is formed 25 and projecting forwardly of the surface of such body to intercept a sledge or analogous tool, thereby to prevent the peening of the metal adjacent to such joint. 30
19. A safe or vault body having a series of inserts located at intervals in the front thereof adjacent to and around the door-joint and projecting forwardly of the surface of such body. 35
20. A safe or vault body having located side by side in the front thereof around the door-joint, a series of wedge-shaped inserts projecting forwardly of the surface of the body. 40
21. A safe or vault door having reinforcing means located in and formed separate from the front thereof and adjacent to its edge and projecting forwardly of such door. 45
22. A safe or vault door having a series of reinforcing devices located at intervals in the front thereof adjacent to its edge. 50
23. A safe or vault door having a series of projecting reinforcing devices located in the door adjacent to its edge. 55
24. A circular safe or vault door having a circular series of wedge-shaped inserts located in the front of such door around and adjacent to its edge. 60
25. A safe or vault door having a series of reinforcing hard - metal inserts interlocked with the metal of such door at the front thereof. 65
26. An integral safe or vault door formed of unmachineable metal having located therein at the front thereof reinforcing means formed of a composition of metal different from the metal composition of which the door is formed. 70
27. A safe or vault comprising a body and a door, each having located in the front thereof around and adjacent to the joint reinforcing means of a composition of metal different 75
- from that of which such body and door are formed. 80
28. A safe or vault comprising an integral body and an integral door, each having located in the front thereof around and adjacent to the door-joint, reinforcing means formed of a composition of metal different from that of which such body and door are formed, and projecting respectively beyond the surfaces of the body and door. 85
29. A safe or vault comprising a body and a door, each having located in the front thereof around and adjacent to the door-joint, reinforcing means comprising a series of wedge-shaped inserts located side by side and projecting beyond the surfaces of the door and body respectively. 90
30. A safe or vault comprising an integral body and an integral circular door, each formed of unmachineable metal and having interlocked in the front thereof entirely around and adjacent to the door-joint a series of protecting-inserts located at intervals. 95
31. A safe or vault door having chrome or analogous hard - steel reinforcing means located therein. 100
32. A heat-treated manganese-steel safe or vault door having chrome or analogous hard-steel inserts located therein. 105
33. An unmachineable cast - steel safe or vault door having chrome or analogous hard-steel inserts located therein during the casting thereof. 110
34. An unmachineable cast - steel safe or vault door having chrome or analogous hard-steel inserts located therein and projecting forwardly of the surface thereof. 115
35. A safe or vault body having chrome or analogous hard-steel reinforcing means located therein and projecting forwardly of the surface thereof. 120
36. An unmachineable-metal safe or vault body having chrome or analogous hard-steel inserts located therein at intervals around its jamb and projecting forwardly of the surface of such body. 125
37. A heat-treated manganese-steel safe or vault body having chrome or analogous hard-steel inserts located therein at intervals, around its jamb and projecting forwardly of the surface of such body. 130
38. A safe or vault made up of a plurality of members with its joint protected by means located in one or both of such members and projecting forwardly thereof. 135
39. A safe or vault made up of several members with its joint protected by a plurality of interlocked inserts located in one or both of such members and formed of chrome or analogous hard steel projecting forwardly of the surface of the metal at such joint. 140
40. A safe or vault body having a portion of its front projecting beyond its door-joint, and protecting-inserts located at intervals in 145

- such projecting portion and projecting beyond the same.
41. A safe or vault comprising a body and a door, the outer contiguous surfaces of the body and door being substantially flush with each other, said body having a projecting portion extending beyond such meeting surfaces, and protecting means located therein and projecting beyond the same and formed of a metal composition different from the metal composition of which the body is formed.
42. A safe or vault comprising a body and a door, the outer contiguous surfaces of the body and door being substantially flush with each other, said body having a projecting portion extending beyond such meeting surfaces, and protecting means located therein and in the door and projecting beyond the same and formed of a metal composition different from the metal composition of which the body and door are formed.
43. A safe or vault comprising a body and a door, the outer contiguous surfaces of the body and door being substantially flush with each other, said body having a projecting portion extending beyond such meeting surfaces, and protecting means located therein and formed of a metal composition different from the metal composition of which the body is formed, and projecting beyond the projecting portion of such body, the inner surface of such projecting means being in substantial alignment with the meeting surfaces of said door and body.
44. A safe or vault comprising a body and a door, the front wall of such body projecting beyond the joint-surface of the door, and said door and body having a pair of annular matching surfaces abruptly terminating the joint-surface at the door, and also having protecting means located therein.
45. A safe or vault comprising a body and a door, the front wall of such body projecting beyond the joint-surface of the door, and said door and body having a pair of annular matching surfaces abruptly terminating the joint-surface at the door, and also having protecting means located therein, comprising hard-metal inserts located around and adjacent to the door-joint.
46. A safe or vault comprising a body and a door, the front wall of such body projecting beyond the joint-surface of the door, and said door and body having a pair of annular matching surfaces abruptly terminating the joint-surface at the door, and also having protecting means located therein, comprising hard-metal inserts located around and adjacent to the door-joint, and projecting beyond the surface of the body and door respectively.
47. A safe or vault comprising a body and a door, the front wall of such body projecting

beyond the joint-surface of the door, and said door and body having a pair of annular matching surfaces abruptly terminating the joint-surface at the door, said body having protecting means located therein and projecting forwardly of such body.

48. A safe or vault comprising a body and a door, the front wall of such body projecting beyond the joint-surface of the door, and said door and body having a pair of annular matching surfaces abruptly terminating the joint-surface at the door, said body having protecting means located therein comprising hard-metal inserts interlocked therein and projecting forwardly of such body.

49. A safe or vault comprising a body and a door, the front wall of such body projecting beyond the joint-surface of the door, and said door and body having a pair of annular matching surfaces abruptly terminating the joint-surface at the door, said door having protecting means located therein.

50. A safe or vault comprising a body and a door, the front wall of such body projecting beyond the joint-surface of the door, and said door and body having a pair of annular matching surfaces abruptly terminating the joint-surface at the door, said door having protecting means located therein, comprising hard-metal inserts interlocked therein.

51. A safe or vault comprising a body and a door, the front wall of such body projecting beyond the joint-surface of the door, and said door and body having a pair of annular matching surfaces abruptly terminating the joint-surface at the door, said door having protecting means located therein, comprising hard-metal inserts interlocked therein, and projecting forwardly thereof.

52. A safe or vault body and a door, such body having its front projecting beyond the outer terminus of its jamb-surface with its base terminating in an annular surface at the outer terminus of and at an angle to such jamb-surface and located to be substantially flush with the contiguous outer surface of the door when the door is closed.

53. A safe or vault comprising a body and a door having at the outer terminus of the door-joint an annular flat surface located within a projecting front portion of the door and body.

54. A safe or vault comprising an unmachinable metal body and an integral unmachinable metal door having at the outer terminus of the door-joint a pair of substantially flush matching annular surfaces located within a projecting front portion of the door and body.

WALTER BRINTON.
